(57) **CLAIM**

The ornamental design for a rotatable display, as shown and described.

DESCRIPTION

FIG. 1 is a front side view of a rotatable display in accordance with our new design;

FIG. 2 is a bottom plan view thereof;

FIG. 3 is a top plan view thereof;

FIG. 4 is a rear side view thereof;

FIG. 5 is a left side view thereof, the right side being a mirror image; and,

FIG. 6 is a front perspective view thereof.

The broken lines in FIG. 1 represent environmental structure forming no part of the claim.
